SUPPLY OF AUXILIARY AIR TO INTERNAL COMBUSTION ENGINES

Filed June 22, 1925

Fig. 4.

INVENTOR
FIG. 3. BY A. H. MOSS,
Watson, Cott. Moss & Grindle,

ATTY.

UNITED STATES PATENT OFFICE.

ARTHUR HARRIMAN MOSS, OF MISTERTON, ENGLAND.

SUPPLY OF AUXILIARY AIR TO INTERNAL-COMBUSTION ENGINES.

Application filed June 22, 1925. Serial No. 38,895.

To all whom it may concern:

Be it known that I, ARTHUR HARRIMAN Moss, a subject of the King of Great Britain, residing at Misterton, in Nottinghamshire, 5 England, have invented certain new and useful Improvements in or Relating to the Supply of Auxiliary Air to Internal-Combustion Engines; and I do hereby declare that the following is a full, clear, and exact description of the same.

This invention relates to devices, for admitting an auxiliary supply of air to the fuel mixture in the induction pipe of an internal combustion engine, of the type providing an annular recess surrounding the induction pipe and separated from the passage therein by a partition having jet-producing apertures through which the air is delivered, the object of the present invention 15 being to furnish improved means for providing the partition with the jet-producing apertures.

It has been proposed to use extra air valves for internal combustion engines in 20 which the air is admitted to the induction pipe between the coils of a spring which is extensible for adjustment purposes, but according to the present invention a coiled wire in annular form is disposed to provide 25 a partition having jet-producing apertures between the annular recess and the passage in the induction pipe. The size and number of the interstices between the coils which provide the jet-producing apertures may be 30 adjusted by replacing the coil with one having a different pitch of the helix in which the wire is coiled, whilst the number of interstices of given width may be varied 35 by the selection of a wire of suitable diameter.

The ends of the annular coil are preferably separated for the admission of air which is deflected into the coil by a plate or ring section connecting its ends, the coil 40 substantially filling the recess and the partition being provided by a portion of each turn of the coil.

Conveniently the coil is retained in place by a washer which forms also one side of 45 the recess.

In the accompanying drawings:—

Figure 1 is an elevation partly in section of a device according to the present invention.

Figure 2 is a sectional side view of Figure 55 1, the section being taken on the line A—A.

Figure 3 is a perspective sectional view on the line B—B of Figure 1.

Figure 4 is a detached elevation of the 60 annular coil and

Figure 5 is a sectional view illustrating a valve for automatically admitting air to the device.

Like reference numerals indicate like 65 parts throughout the drawings.

The device illustrated comprises a body 1 having a boring 2 adapted to form part of the induction passage leading from the carburetor to the cylinder or cylinders of an internal combustion engine. The body 70 1 conforms in outline to the flanges by which the induction pipe is bolted to the carburetor and is intended to be fitted in place between these parts by means of bolt holes 3.

The body 1 is formed with an annular recess 4 entirely surrounding the part of the induction passage constituted by the boring 2, the recess 4 thus forming an enlargement of the induction passage. The recess 4 is continued by a cavity in the body 1 at 5 to 75 an opening 6 to the atmosphere, and this opening is controlled by a suitable valve 7 which is spring-controlled as indicated at 8 and is capable of being operated by hand 80 from the driver's seat or other suitable position by means of Bowden wire 9.

A length of coiled wire 10 is curved into an annular form as indicated in Figure 4 and is disposed in the recess 4, for which purpose one side of the recess is constituted 90 by a removable washer 11 which is let into one side of the body 1 so as to be flush with the outer surface of the body. The annular coil 10 and the washer 11 may be retained 95 in place by set screws 12 having countersunk heads engaging the edges of the washer 11. If desired, however, both side walls of the recess 4 may be integral with the body 1, the annular coil 10 being inserted into the recess from the boring 2. In either case 100 the recess 4 may be undercut to any desired shape as for example by the provision of a flange or flanges or series of projections, the annular coil 10 being threaded through at the junction of the recess 4 with the cavity 105 5 if the washer 11 is not provided.

The diameter of the turns of wire comprising the annular coil 10 preferably cor-

responds to the width and depth of the recess 4 so that the coil substantially fills the recess as indicated in the drawings. The ends of the coil 10 are separated and the gap 5 between them is disposed at the junction of the recess 4 with the extension cavity 5. The ends of the coil are connected by a plate or impervious ring section 13 which is curved transversely to fit approximately one half of the interior of the coil 10 and is also curved longitudinally to correspond with the curvature of the annular coil which is coaxial with the boring 2. The plate 13 is disposed with its ends engaged inside the ends 15 of the annular coil 10 and with its concave surface facing the extension cavity 5 and air inlet 6. In this manner when the valve 7 is open air will be drawn by the suction of the engine through the inlet 6 along the cavity 5 and will be deflected by the plate 13 into the interior of the annular coil 10, whence it issues into the induction passage through the interstices of those portions of the turns comprising the coil which separate 25 the recess 4 from the induction passage.

If it be desired wholly to prevent the direct passage of air from the cavity 5 into the induction passage the spaces at the sides of the plate 13 may be closed by suitably shaping either the plate 13 or the adjacent parts 30 of the body 1. As an alternative to such special shaping the plate 13 may be formed to fit outside instead of inside the ends of the annular coil 10.

As a modification the parts may be so shaped and disposed that the annular coil 10, instead of substantially filling the recess 4, leaves a space for the passage of air in the recess, the air then passing through both 40 the outer and the inner interstices of the annular coil 10. In this case the annular coil 10, instead of being circular in transverse section may be of a flattened rectangular or elliptical shape disposed at the edges of 45 the recess 4.

If desired the annular coil 10 may easily be replaced by another in which the number or size of the interstices between the coil-turns thereof are varied in order to adjust the volume of air admitted through them to suit different circumstances, the number of interstices being varied according to the diameter of the wire from which the coil is made, whilst both the number and 55 size of the interstices may be adjusted by varying the pitch of the coil-turns.

If desired a priming tap or petcock 14 may be fitted to the device to communicate with the passage 5 for the purpose of introducing a priming charge to facilitate the starting of the engine.

If desired air may be automatically admitted to the recess 4 when the engine reaches a pre-determined speed by means of the spring controlled non-return inlet valve

illustrated in Figure 5. This valve may be attached to the body 1 in place of either of the plugs 15 or 16 which normally close openings from the atmosphere to the passage 5 and to a second passage leading to 70 the recess 4. Such automatic admission may be provided either in addition to or instead of the hand controlled valve 7.

What I claim is:—

1. In a device for admitting an auxiliary supply of air to the fuel mixture in the induction pipe of an internal combustion engine, the combination of a body having a boring adapted to form part of the induction pipe and provided with an annular recess forming an enlargement of that boring, a valve communicating by a passage in the body with the recess and a coiled wire in annular form disposed to provide a partition having jet-producing apertures between the recess and boring, substantially as specified. 75

2. In a device for admitting an auxiliary supply of air to the fuel mixture in the induction pipe of an internal combustion engine, the combination of a body having a boring adapted to form part of the induction pipe and provided with an annular recess forming an enlargement of that boring, a valve communicating by a passage in the body with the recess, a coiled wire in annular form disposed to provide a partition having jet-producing apertures between the recess and boring, the ends of the annular coil being separated at the said passage and an impervious ring section connecting the coil ends across said passage to deflect air into the coil, substantially as specified. 80

3. In a device for admitting an auxiliary supply of air to the fuel mixture in the induction pipe of an internal combustion engine, the combination of a body, having a boring adapted to form part of the induction pipe and provided with an annular recess forming an enlargement of that boring, a movable washer forming one side of the recess, a valve communicating by a passage in the body with the recess, and a coiled wire in annular form disposed to provide a partition having jet-producing apertures between the recess and boring, substantially as specified. 85

4. In a device for admitting an auxiliary supply of air to the fuel mixture in the induction pipe of an internal combustion engine, the combination of a body, having a boring adapted to form part of the induction pipe and provided with an annular recess forming an enlargement of that boring, a movable washer forming one side of the recess, a valve communicating by a passage in the body with the recess, a coiled wire in annular form disposed to provide a partition having jet-producing apertures 90

tures between the recess and boring, the ends of the annular coil being separated at the said passage, an impervious ring section connecting the coil ends across said passage to deflect air into the coil, a priming tap communicating with the said passage, a second passage to the recess from the

atmosphere and a spring-controlled non-return inlet valve to the second passage, substantially as specified. ¹⁰

In testimony whereof I hereunto affix my signature.

ARTHUR HARRIMAN MOSS.
